UNITED STATES PATENT OFFICE.

FRANK E. CUDELL, OF CLEVELAND, OHIO.

SEWER-GAS TRAP.

1,027,997.

Specification of Letters Patent.

Patented May 28, 1912.

Application filed January 19, 1912. Serial No. 672,057.

To all whom it may concern:

Be it known that I, FRANK E. CUDELL, a citizen of the United States, resident of Cleveland, county of Cuyahoga, and State of Ohio, have invented a new and useful Improvement in Sewer-Gas Traps, of which the following is a specification, the principle of the invention being herein explained and the best mode in which I have contemplated applying that principle, so as to distinguish it from other inventions.

My invention has reference to a sewer-gas trap and more particularly to the type commonly known as pot traps.

15 The object of the invention is the provision of a trap of this character which will more certainly insure the refilling or resealing to a required depth of broken water seals.

20 The said invention consists of means hereinafter fully described and particularly set forth in the claims.

The annexed drawings and the following description set forth in detail certain means embodying my invention, the disclosed means, however, constituting but one of various mechanical forms in which the principle of the invention may be applied.

Figure 1 is an elevation partly in section of a trap embodying my invention. Fig. 2 is a section on lines II-II of Fig. 1 looking in the direction of the arrows. Fig. 3 is an interior modification of the view shown in Fig. 1. Fig. 4 is a cross-section on lines IV-IV of Fig. 3 likewise looking in the direction of the arrows. Fig. 5 is a further modification of the view disclosed in Fig. 1 showing one portion thereof transposed and adjustable. Fig. 6 is a view of a further modification applicable to bath tubs. Fig. 7 is an end elevation of still another modification. Fig. 8 is a section on lines VIII-VIII in Fig. 7, looking in the direction of the arrows. Fig. 9 is a section on lines IX-IX of Fig. 8 looking in the direction of the arrows. Fig. 10 is an end view of a further modification specifically of the form disclosed in Figs. 7, 8 and 9. Fig. 11 is a section on lines XI-XI of Fig. 10, again looking in the direction of the arrows and having the position of one portion transposed in dotted lines. Fig. 12 is a modification of Fig. 11 after the manner of the differentiation feature suggested in Fig.

55 Fig. 13 is an end elevation of a final

modification. Fig. 14 is a side view of same partly in section, further showing one portion in dotted lines in an altered position. Fig. 15 is a top plan of the final modification represented by Figs. 13 and 14.

Referring first to Fig. 1, the construction comprises as an entirety a downwardly extending inlet duct A provided with an angular inlet opening a^1 , a downwardly extending outlet duct Z provided with an angular outlet opening proper z^1 , and finally the cylindrical pot B positioned intermediate of the ducts A and Z, and in communication with both the lower inlet a' and the diagonally opposite upper outlet z^1 . The top of the pot B is in this instance closed, whereas the bottom is open and internally provided with screw-threads b^2 . The pot B shown is furthermore composed of an upper and lower section integrally joined at b^3 by welding or other approved means. A clean-out cover C provided with finger lugs c^1 is provided with complementary exterior screw-threads and is adapted to be screwed into the bottom opening of the pot B as clearly seen in Fig. 1. The cover C supports centrally an upwardly extending tubular shaped partition c^2 . This partition is integral with the cover C and furthermore likewise composed of two parts welded at c^3 in any approved manner. The primary tubular partition c^2 is itself provided with upper and lower laterally projecting portions respectively designated at c^4 and c^5 . These angular portions project in accordance with this specific conception in opposite directions and are furthermore flared to present divergent openings as most clearly outlined in Fig. 2. As so formed and positioned, the flared portions c^4 and c^5 are adapted to more readily register respectively with the outlet opening z^1 and the inlet opening a^1 . The portions c^4 and c^5 are furthermore spaced a slight distance from the annular surfaces surrounding the outlet and inlet openings as clearly seen in both Figs. 1 and 2. These annular spaces are respectively designated by the reference characters c^6 and c^7 .

As thus described and as should now be apparent the operation of my trap is as follows:—Liquid after being discharged downwardly through the inlet duct A passes up through the substantially central duct or passage c^8 inclosed by the partition c^2 and

thence into the outlet duct Z preparatory to final discharge. During its passage, however rapidly, through the duct c^8 , a considerable portion of the flow will finally 5 have entered the annular space or refilling chamber b^4 which surrounds the duct c^8 and specifically through both the spaces c^6 and c^7 . When there is a discharge of water in considerable quantity, the water diverted 10 through these spaces c^6 and c^7 proves to be sufficient to completely fill the surrounding annular space. While the siphon action, due to long unvented waste pipes is effective, the discharged liquid will be almost entirely 15 drawn from the duct c^8 , whereas the water in the annular space b^4 surrounding such partition, because of the constricted openings c^6 and c^7 which are momentarily closed by the rapid rush of air, will remain 20 comparatively quiescent. Consequently after the siphon action is over, this accumulated supply of liquid will seek its true level and hence establish the required water seal.

25 A special note is here made of the inventive advantages which my construction insures in practice. By having the partition c^2 with its upper and lower oppositely projecting angular portions c^4 and c^5 centrally disposed the normal course of the main current of the liquid through the pot is in fact 30 the substantial diagonal, and hence the shortest route, between the diagonally opposite inlet and outlet openings. By reason 35 of this circumstance, the siphon action by being quite direct is calculated to have less of an effect upon either the air or water which may chance to be contained in the annular space b^4 of the pot. Consequently, 40 as already intimated considerably less of a disturbing effect will be found caused with reference to the water that has been stored for the purpose of forming the final water seal. Thus a refilling chamber b^4 of maximum 45 volume relative to the volume of the entire pot B is provided and the maximum average supply of water maintained within it. By having the partition c^2 attached to the clean-out cover, an obviously improved 50 facility for cleaning the interior of the trap is presented. Finally recognizing full well the need for a compact structure as a whole the maximum volume of space, for the purpose of serving the function of a refilling 55 chamber in traps of this kind, is provided.

Considering now the modification disclosed in Figs. 3 and 4, it will be noted that the difference resides merely in the shape and position of the partition c^2 . In this 60 case, the partition instead of being in and of itself a duct merely assumes the nature of a parabolic curve, having its concave side adjacent and facing the outlet side of pot B. Furthermore, by reason of this differentiation 65 from the form shown in Figs. 1 and 2,

only a lower though longer angular portion c^5 is required and also in place of the upper annular space c^6 found in the previous form, a pair of longitudinally extending spaces c^6 c^7 are provided. The refilling chamber b^4 70 surrounding the constricted duct or passage c^8 as inclosed by the partition c^2 is necessarily also altered to assume the shape best observed in Fig. 4. The operation is of course practically similar. 75

Referring next to Fig. 5, the differentiation from Fig. 1 will be found to rest in the provision of the outlet opening z^1 in the top rather than the upper side of the pot B. The outlet duct Z instead of being integrally 80 associated with the pot B around such a side opening is adjustably secured thereto through the agency of the union c^9 which being loosened permits the outlet duct Z to be rotated to assume various positions of 85 partial rotation and so adapt itself to a like number of accommodations. 85

Considering next the bath tub modification shown in Fig. 6, it will be seen that this is shown seated in the customary manner 90 in the floor F a portion of which appears in section. According to this form, the inlet duct A finds entrance to the side of the pot and near the top whereas the acutely bent outlet duct Z communicates with the bottom of the pot, and preferably as shown with the center thereof. The partition member c^2 is again secured to the cover which is in this instance situated at the top of the pot B in order to rest above the floor F in 95 the usual manner. The design of the partition c^2 is identical, save for being reversed to that shown in Fig. 5. The principle of the more assured refilling operation remains precisely similar by reason of the 100 lower and upper spaces c^6 and c^7 . 105

Looking on to the next modification represented in Figs. 7, 8 and 9, it will be seen that the differentiating feature is radically associated with both the shape and location 110 of the pot B. From a closer inspection of these figures, the pot B will be seen to project laterally with reference to the normally assumed position of the trap as a whole and is in consistence provided with a lateral 115 clean-out cover. The course of the liquid under process of discharge through this type of trap is downwardly through the pot and thereafter upwardly through an acute bend imparted to the outlet duct Z. As most 120 clearly appearing in Fig. 9, the cover C supports a removable partition c^2 comprising a horizontally projecting pipe to which is attached an upright curved surface with concave side similarly adjacent and facing 125 the outer side of the pot,—i. e., that side of the pot nearest the outlet duct Z. In this form, the constricted refilling channels or spaces c^6 and c^7 are continuous from the top to the bottom of the pot somewhat after 130

the manner of the upright spaces c^6 and c^7 of the first modification shown in Figs. 3 and 4. The horizontal pipe portion of the partition c^2 has openings c^{10} to permit its interior to add volume to the refilling chamber b^4 and is furthermore screw-threaded to the cover C at c'' . This form likewise compels the main bulk of the liquid to take the shortest route possible through the pot and hence occasions a proportionately reduced disturbance of the liquid which is in the refilling chamber b^4 and consonantly precludes a proportionately greater amount of the water from being withdrawn therefrom during an unusually strong siphon action.

Figs. 10 and 11 differ from the previous form considered primarily in the direction of passage of the liquid discharged through the pot B and hence necessarily also in the reversal of the shape of the inlet and outlet ducts A and Z. As will be most readily apparent in Fig. 10, the inlet duct A is provided with the acute bend intended to contain the water seal and communicates with the bottom of the pot rather than the top. If desired, the outlet duct Z may be made as suggested in dotted lines in Fig. 11 to complete a half S with reference to the construction as a whole rather than a full S.

Fig. 12 comprises a combination of the forms shown in Figs. 5 and 10. The direction of passage of the liquid through this form is identical with that of Figs. 10 and 11, whereas the outlet duct Z is adjustably connected with the top of the pot through the medium of a union c^9 and for a practical purpose precisely similar to that stipulated in connection with the description of Fig. 5.

With final reference to the form disclosed in Figs. 13, 14 and 15, it will be seen that the change consists again merely in a transposition and hence as a prerequisite the shape of the inlet and outlet ducts. The inlet duct A approaching the pot from above and to one side of its median line, passes downwardly below the same as best seen in Fig. 13, where it is bent toward such imaginary line as also seen in Fig. 15 and finally upwardly so as to communicate with a lower inlet opening a^1 disposed on one median line of the pot, and with the main passage c^8 surrounded by the partition c^2 . The outlet duct Z is symmetrically bent in such a way that it will avoid the inlet duct A and then communicate with the pot directly above the inlet a^1 . The interior of the pot B and specifically the formation of the partition c^2 with its resultant substantially vertical spaces c^6 c^7 is precisely similar to that disclosed in Fig. 9, and hence not again similarly represented in this connection. If desired in this form the outlet pipe may alternatively approach the pot as indicated in dotted lines in Fig. 14.

Attention is by way of summary finally directed to the pair of distinct structural arrangements which are found throughout all the views and all of which because of a precisely similar operation in each of the modifications are respectively based upon a pair of common inventive principles. One theory consists in always permitting the bulk and hence the current of flow to follow the shortest route between the inlet and outlet openings of the particular pot irrespective of their relative locations. The succeeding siphon draft will then have a course of least resistance provided, along which its excessive drainage proclivities will be effectively dissipated by a rush of air in place of water. Consonantly the larger portion of the water stored in the surrounding refilling chamber is retained and a more reliably uniform supply assured. The other feature common to all the views is the attachment of the formative partition c^2 to the clean-out cover, whereby the removal of the latter exposes and so facilitates the accessibility of any suitable cleansing appliances to all interior surfaces.

Having fully described my invention, what I claim is:

1. A sewer gas trap comprising the combination of a pot provided with upper and lower openings, and an interiorly positioned duct communication with said openings and with said pot, said duct having flared portions adjacent said openings.

2. A sewer gas trap comprising the combination of a pot provided with upper and lower openings, a removable cover for said pot, a removable duct interiorly connecting said openings, said duct communicating with said pot adjacent each such opening.

3. A sewer gas trap comprising the combination of a pot provided with inlet and outlet openings, a cover removably secured thereto, and a duct attached to said cover and connecting said openings, said duct being non-contiguous with said pot.

4. A sewer gas trap comprising the combination of a pot, provided with inlet and outlet openings, a duct-forming member movably positioned within said pot, said duct itself provided with flared end openings communicating with said inlet and outlet openings and with said pot.

5. A sewer gas trap comprising the combination with a pot having inlet and outlet openings; and a partition forming an interior duct in direct communication with said openings, said duct having restricted communications with said pot adjacent said openings.

6. A sewer-gas trap comprising the combination of a pot having upper and lower openings, a removable member secured to said pot, and a partition attached to such member and forming a duct extending across

said pot in the direct line of said openings, said duct communicating with said pot near each such opening.

7. A sewer-gas trap comprising the combination of a pot having a lower inlet and an upper outlet opening, a cover removably secured to said pot, and a partition member attached to said cover and projecting substantially across said pot and between said openings, said member being bent and form-

ing a duct extending in the line of said openings, said member being furthermore provided with upper and lower slots communicating with said pot.

Signed by me, this fifteenth day of Jan- 15
uary 1912.

FRANK E. CUDELL.
